UNITED STATES PATENT OFFICE.

JOHN H. FOX, OF PITTSBURGH, PENNSYLVANIA, ASSIGNEE TO PITTSBURGH PLATE GLASS COMPANY, A CORPORATION OF PENNSYLVANIA.

EDGE-HOLDING DEVICE FOR SHEET-GLASS MACHINES.

Application filed May 2, 1924. Serial No. 710,569.

To all whom it may concern:

Be it known that I, JOHN H. FOX, a citizen of the United States, and a resident of Pittsburgh, in the county of Allegheny and State of Pennsylvania, have made a new and useful invention in Improvements in an Edge-Holding Device for Sheet-Glass Machines, of which the following is a specification.

10 The invention relates to apparatus for use with a glass sheet drawing machine. It has for its object the provision of an improved automatic means for preventing the edges of the sheet from moving inward during the drawing operation and gradually reducing the width of the sheet. One embodiment of the invention is illustrated in the accompanying drawings wherein:

Figure 1 is a diagrammatic side elevation, 20 showing the drawing apparatus with which the edge holding device constituting the present invention is preferably used. Fig. 2 is a side elevation of one of the edge holding devices in position of use. Fig. 3 is an end elevation of the device of Fig. 2. Fig. 4 is a detail, plan view of the device for reciprocating the operating rack. And Fig. 5 is a section on the line V—V of Fig. 2.

Referring first to the general arrangement of parts as illustrated in Fig. 1, the principal parts may be enumerated as follows: 1 is the drawing tank or extension carrying a molten bath of glass 2 in communication with a suitable melting tank, not shown; 3 and 4 are endless belts, preferably of asbestos fabric for continuously drawing the sheet of glass 5 from the molten bath; 6 and 7 are the driving pulleys for the belts, such belts being driven from a suitable motor, not shown; 8 and 9 are solid steel bars circular in cross section lying in the lower ends of the belts and serving by reason of their weight to hold the belts in tension; 10 are a series of rolls back of the inner flights of the belts for pressing the belts against the glass, such rolls being yieldingly held inward by means of springs or weights, not shown; 11 and 12 are pairs of driven rolls covered with asbestos for assisting in the pulling of the sheet; and 13 is one of the edge holding devices to which the present invention is particularly directed, it being understood that such edge holding devices may be used in connection with any form of drawing mechanism, although the one as

briefly illustrated and described is preferred.

It will also be understood that an edge holding device, such as that shown in Fig. 2 is applied at each side of the sheet, but for brevity of description and illustration only one of such device is shown and described. The framework upon which the device is mounted consists of the bottom plate 14, the inclined angle members 15 (Figs. 2 and 3), 60 the brace members 16 and the cap member 17 riveted to the angle members 15 as indicated in Fig. 5. This cap member is provided with the forwardly projecting arms 17^a carrying the transverse rod 19, upon 65 which is mounted the guide member 18, such guide member being adjustable about the rod 19 as an axis. The rear end of the guide member 18 is adjusted by means of the three bolts 20 and 21. The bolts 20 hold 70 the end of the guide member 18 against downward movement, while the bolt 21 bearing against the top of the guide member holds it against upward movement. By 75 means of these three bolts, the guide member 18 and the parts carried thereby may be adjusted around the axis 19 to vary the 80 position of the operating tool as hereinafter described.

Slidably mounted in the guide member 18 is the plate 22, bolted at its rear end to the casting 23. The plate 22 has bolted to its lower side the plate 24 and the forward end of this plate is turned downward as indicated at 25 (Fig. 2) and acts as a support 85 for the guide pipe 26, such pipe being clamped at its forward end to the part 25 by means of the nuts 27.

Extending through the guide pipe 26 and the casting 23 is the rod 28 which carries 90 the rack bar 29 for operating the edging tool. The bar 28 is normally pressed rearwardly by the spring 30 and is moved forwardly by the plate 31 provided with the pins 32. The plate 31 is mounted upon a 95 shaft 33 driven from suitable mechanism, not shown, and the rotation of this plate causes the pins 32 to successively engage a cam member 34 carried upon the rear end of the rod 28. The sliding support of the plate 22 provides for the adjustment of the entire mechanism, including the casting 23, horizontally toward and from the edge of the 100 glass sheet to vary the position of the edging tool to meet conditions. The plate 22 is 105 110

clamped in any desired longitudinal position of adjustment by means of the set screw 17^b (Fig. 2) which extends down through the guide member 18 and bears against the 5 top of the plate 22.

The lower end of the part 25 also acts as a guide support for a rod 35 which carries at its forward end a block 36. This block has an upwardly extending portion 37 10 which acts as a guide for the rack bar and also carries a transverse pin 38 upon which are mounted the finger bars 39 for holding out the edge of the glass sheet. Intermediate the finger bars 39 is a spur gear 40 15 in engagement with the rack so that the reciprocation of the rack bar serves to swing the finger bars from the position indicated in full lines in Fig. 2 to the vertical dotted line position. Mounted in the casting 23 is 20 the reduced shank portion 41 of the operating sleeve 42, and to the forward end of this reduced shank portion is pinned a collar 41^a so that the sleeve 42 is swiveled in the casting 23. The rear end of the rod 35 is 25 threaded into the sleeve 42 so that by rotating the sleeve, the rod 35 and the block 36 may be adjusted back and forth. This gives an adjustment of the stroke of the finger bars 39 so that such finger bars may be 30 pressed into the glass a greater or less degree depending on conditions.

In order to cool the finger bars 39 in their uppermost position, as indicated in the dotted lines, the water cooled manifold 43 is 35 used, such manifold being supported upon the arms 44 and having an inlet pipe 45 on one side and an outlet pipe on the other side, whereby a cooling fluid may be circulated through the manifold. The arms 44 are 40 pivoted at 46 upon the block 36 and are held in the position illustrated by means of the spring 47, the arms carrying at their lower ends a stop portion 48 which bears against stop portions on the block 36, so that the 45 movement of the manifold to the left is limited by these means. When it is desired to remove the plate 22 to the right together with all the operative parts carried thereby, the set screw 17^b is loosened and the apparatus 50 pulled to the left. The mounting of the manifold 45 on the arms 44 so that it can swing to the right permits such manifold and the arms 44 to move down beneath the guide 18 as the machine is withdrawn to 55 the left.

The apparatus is capable of wide variation in the matter of details of construction, as many forms of mechanism might be employed for swinging the finger bars in the 60 desired path of movement and for securing the adjustment of these fingers. The broad invention contemplates any and all means of securing the oscillation of the finger members back and forth on the same line of 65 travel for both movements and any and all

means for cooling the finger bars when in their position of retraction, although the method of cooling by contact with a manifold or other similar member is preferred. The finger bars 39 are preferably secured 70 together and operated in unison, thus providing a fork enclosing the edge of the sheet, but this is not necessarily the case, as the same function would be secured, although in a less convenient and simple form, by 75 having these bars operable independently and not in unison. The primary consideration is the thinning of the tapering base of the sheet at the edge by a tool which oscillates back and forth vertically and strips down the glass at the tapered base of the sheet, such tapered base being indicated in dotted lines at 49 in Fig. 3. In case the glass in such base is cooled and thinned by 80 the finger bars to too great an extent, the period between oscillations of such bar may be increased by slowing down the speed of operation of the shaft 33, or the depth to which the bars are pressed into the glass may be decreased by adjusting the bar 35 to 85 the right. The locus of the oscillation may be also adjusted by adjusting the guide member 18 about its supporting pivot 19 by means of the bolts 20 and 21 as heretofore described. In case the position of the edge 90 of the sheet changes so that the finger bars do not operate at the proper position with respect to such edge, the entire apparatus may be moved in and out by loosening said screw 17^b and sliding the plate 22 in or out. 100

What I claim is:

1. In combination with apparatus for drawing a glass sheet from a molten bath, means for preventing inward movement of the edge of the sheet comprising a pair of fingers spaced apart so that they will straddle the edge of the sheet, and mechanism for moving said fingers at intervals downward along the edge of the sheet and into the tapering base thereof to thin it and then back from such position along substantially the same path. 105

2. In combination with apparatus for drawing a glass sheet from a molten bath, means for preventing inward movement of the edge of the sheet comprising a pair of fingers spaced apart so that they will straddle the edge of the sheet, mechanism for moving said fingers at intervals downward along the edge of the sheet and into the tapering base of the sheet to thin it and then back from such position along substantially the same path, and means for cooling the fingers upon their return to their starting position. 110

3. In combination with apparatus for drawing a glass sheet from a molten bath, means for preventing inward movement of the edge of the sheet comprising a pair of fingers spaced apart so that they will 115

straddle the edge of the sheet, mechanism for moving said fingers at intervals downward along the edge of the sheet and into the tapering base of the sheet to thin it and then back from such position along substantially the same path and a cooling member with which the fingers are adapted to contact when returned to starting position.

4. In combination with apparatus for drawing a glass sheet from a molten bath, means for preventing inward movement of the edge of the sheet comprising a pair of fingers spaced apart so that they will straddle the edge of the sheet, and pivoted opposite the edge of the sheet, and mechanism for swinging the fingers at intervals about their pivot so that they move downward along the edge of the sheet and into the tapering base thereof to thin it and then back from such position along substantially the same path.

5. In combination with apparatus for drawing a glass sheet from a molten bath, means for preventing inward movement of the edge of the sheet comprising a pair of fingers spaced apart so that they will straddle the edge of the sheet, a cooling tool, and mechanism for moving said tool at intervals (1) downwardly along the side of the sheet at its edge and in close proximity thereto and into the tapering base of the sheet to thin such base at the edge of the sheet, (2) and then back from such position along substantially the same path as that pursued in the forward movement.

6. In combination with apparatus for drawing a glass sheet from a molten bath, means for preventing inward movement of the edge of the sheet comprising a cooling tool, means for cooling the tool and mechanism for moving said tool at intervals (1) downwardly along the side of the sheet at

its edge and in close proximity thereto and into the tapering base of the sheet to strip the glass downwardly and thin such base at the edge of the sheet, (2) and then back from such position along substantially the same path as that pursued in the downward movement.

7. In combination with apparatus for drawing a glass sheet from a molten bath, means for preventing inward movement of the edge of the sheet comprising a cooling tool, cooling means with which the tool contacts while in starting position, and mechanism for moving said tool at intervals (1) downwardly along the side of the sheet at its edge and in close proximity thereto and into the tapering base of the sheet to strip the glass downwardly and thin such base at the edge of the sheet, (2) and then back from such position along substantially the same path as that pursued in the downward movement.

8. In combination with apparatus for drawing a glass sheet from a molten bath, means for preventing inward movement of the edge of the sheet comprising a cooling tool, means for cooling the tool while in its initial or starting position, and mechanism for moving said tool at intervals (1) downwardly along the side of the sheet at its edge and in close proximity thereto and into the tapering base of the sheet to strip the glass downwardly and thin such base at the edge of the sheet, (2) and then back from such position along substantially the same path as that pursued in the downward movement.

In testimony whereof, I have hereunto subscribed my name this 31st day of March, 1924.

JOHN H. FOX.
